Specification for Design.

Patented Aug. 10, 1920.

Application filed April 19, 1920. Serial No. 375,181. Term of patent 14 years.

To all whom it may concern:

Be it known that I, JOSEPH W. GOSLING, a citizen of the United States, residing at Schenectady, in the county of Schenectady, State of New York, have invented a new, original, and ornamental Design for a Band for a Lamp-Globe, of which the following is a specification, reference being had to the accompanying drawing, forming a part thereof.

The accompanying drawing is a perspective view of my band for a lamp globe.

What I claim is,—

The ornamental design for a band for a lamp globe as shown.

In witness whereof, I have hereunto set my hand this 14th day of April, 1920.

JOSEPH W. GOSLING.
